UNITED STATES PATENT OFFICE.

ERWIN GRAVES, OF CAMDEN, NEW JERSEY, ASSIGNOR TO THE CAMDEN IRON WORKS, OF SAME PLACE.

HYDRAULIC RIVETING-MACHINE.

SPECIFICATION forming part of Letters Patent No. 615,547, dated December 6, 1898.

Application filed August 25, 1897. Serial No. 649,466. (No model.)

To all whom it may concern:

Be it known that I, ERWIN GRAVES, a citizen of the United States, and a resident of Camden, New Jersey, have invented certain 5 Improvements in Hydraulic Riveting-Machines, of which the following is a specification.

My invention relates to riveting or punching machines operated by water, air, or other 10 fluid under pressure, the object of my invention being to provide means for effecting the squaring or leveling of two or more super- 15 posed plates which are being riveted together or are having openings punched therein, such 20 squaring or leveling of the plates being brought about by the action of a preliminary pressing device which acts in advance of the riveting die or punch and serves not only to press the plates firmly together, but also to 25 press them squarely upon the counter-die, so that the faces of the plates will be brought into position parallel with the face of said counter-die, or in the case of a portable riveter or punch to square the machine over the work and hold it rigidly in the proper position, thus preventing any deformation of the rivet.

In the accompanying drawings, Figure 1 is a side view of sufficient of a riveting or punching 30 machine to illustrate my invention. Fig. 2 is a top or plan view of the same. Fig. 2^a is an enlarged view of the valve-chests and valves of the machine. Fig. 3 is an enlarged 35 view, partly in elevation and partly in transverse section, on the line x x, Fig. 1; and Figs. 4, 5, and 6 are views illustrating certain modifications of the invention.

I have in the present instance illustrated 40 my invention as applied to a hydraulic riveting-machine of the jaw type, the upper projecting jaw 1 having the cylinder 2 for the reception of the piston 3, whose rod 4 carries the upper riveting-die, the lower projecting jaw 5 of the frame carrying the lower die 6. 45 It should be understood, however, that my invention is not limited to this particular type of machine; but it may be applied to any ordinary form of riveting-machine using air, water, or other fluid under pressure as 50 the motive power, or it may be applied to machines for punching as well as for riveting.

In Fig. 1, 7 represents the pipe through which air, water, or other fluid under pressure is conveyed to the machine, said pipe having three branches 9, 10, and 11, the branch 55 9 leading to the inlet-branch 12 of a valve-chest 13, which has a distributing branch 14 and an exhaust branch 15 and contains a valve of any suitable character whereby said branch 14 may be placed in communication 60 either with the branch 12 or with the branch 15 of the chest, said valve having a projecting stem 16.

The branch pipe 10 leads to the inlet branch 17 of a smaller valve-chest 18, having a distributing branch 19 and an exhaust branch 20, this chest likewise containing a valve 65 similar to but of less area than the valve of the chest 13 and like it having a projecting stem 16^a. The valve-chests 13 and 18 occupy 70 reverse positions, so that downward movement of the valve in the chest 18 is required in order to put the inlet branch 17 of the same into communication with the distributing branch 19, upward movement of the valve 75 cutting off the flow from the branch 17 to the branch 19 and putting the latter into communication with the exhaust branch 20, the movement of the valve in the chest 13 being the reverse of this. 80

Both of the valve-stems 16 and 16^a are connected to a single operating-lever 21, so that by the operation of this lever the valves of both of the chests 13 and 18 can be operated, the movement of the valve in the chest 18 always preceding that of the valve in the chest 13 because of the less resistance to such movement due to the smaller area of said valve in the chest 18. In moving the handle in either direction, therefore, the connection between 90 said handle and the valve-stem 16 serves as a fulcrum until the further movement of the valve-stem 16^a is arrested by reason of its valve reaching the limit of its movement in the valve-chest 18, whereupon the connection 95 between the lever 21 and the stem 16^a becomes the fulcrum, and further movement of said lever effects movement of the valve in the chest 13.

The distributing branch 14 of the valve-chest 13 communicates through a pipe 22 with the upper end of the cylinder 2, above the pis-

ton 3 therein, and the distributing branch 19 of the valve-chest 18 communicates through a pipe 23 with a branched or forked pipe 24, which supplies motive fluid to the upper ends 5 of a pair of cylinders 25, located one on each side of the main cylinder 2, at the lower part of the same, where said cylinder is contracted for the passage of the piston-rod 4, as shown in Fig. 3.

10 Each cylinder 25 contains a piston 26, with rod 27, which passes through a suitable stuffing-box at the lower end of the cylinder, these piston-rods 27 being connected to the squaring device 29, which in the present instance 15 consists of a short tube surrounding the upper riveting-die 30, which is carried by and projects from the lower end of the piston-rod 4, as shown in Fig. 3. The tube 29 slightly underlaps the piston-rod 4 and has lateral flanges 20 31, which are secured to the lower ends of the piston-rods 27.

25 The branch 11 of the pipe 7 is forked and supplies motive fluid to the lower ends of the cylinders 25, so that constant pressure is maintained beneath the pistons 26, tending to raise the same and with them the squaring device 29, piston-rod 4, and piston 3, as shown in Figs. 1 and 3, this being the normal or inoperative condition of the machine, and the 30 valves in both of the chests 13 either occupying an intermediate or inoperative position, so as to cut off the distributing branch of each chest from both the inlet or exhaust branches, or occupying such position as to open communication between the distributing branch of 35 each chest and the exhaust branch.

40 When it is desired to operate the machine, downward pressure is exerted upon the outer end of the lever 21, so as to first move downward the valve in the chest 18 and permit of the flow of motive fluid through the pipes 23 and 24 into the upper ends of the cylinders 25, so as to cause the descent of the pistons 26 therein, owing to the greater area presented to 45 pressure by the tops of said pistons than by the under sides of the same. This causes the descent of the squaring device 29 and the pressing of the same firmly upon the plates resting upon the lower die 6, and this is immediately followed by the descent of the piston 3, piston-rod 4, and upper riveting-die 30, owing to the fact that the upward movement 50 of the valve in the chest 13 immediately follows the downward movement of the valve in the chest 18 as downward pressure continues to be exerted upon the operating-lever 21. After the operation has been completed the parts are restored to the former position by raising the lever 21, so as to effect the lifting of the valve in the chest 18, followed by the descent of the valve in the chest 13, thus opening to the exhaust first the upper ends 55 of the cylinders 25 and then the upper end of the cylinder 2, the rise of the squaring device causing the simultaneous rise of the piston-rod 4 and piston 3, owing to the engage- 60

ment of said squaring device with the lower end of said piston-rod 4.

While I prefer in all cases to use the duplex cylinder for operating the squaring device, a single-cylinder construction may, if desired, be employed without departing from the main features of my invention, and in Figs. 4 and 5 I have illustrated two different forms of such single-cylinder-operating mechanism for 75 the squaring device.

In the construction shown in Fig. 4 the piston-rod 4^a is at one side of the piston 3^a and the cylinder 25^a is beneath the overhanging portion of said piston, the piston-rod 27^a 80 being connected to a stem 32, projecting upwardly from the squaring device, at one side of the latter, and guided in a downward continuation of said cylinder 25^a.

In the construction shown in Fig. 5 the piston-rod 4^b is also at one side of the piston 3^b and the cylinder 25^b is beneath the overhanging portion of said piston, but the piston-rod 27^b projects upwardly from the piston 26^b instead of downwardly and is connected to a lateral flange 33 on a sleeve 34, which surrounds the piston-rod 4^b and carries at its lower end a squaring device 29^b. In this case the arrangement of the pipes for supplying motive fluid to the cylinder 25^b will be the reverse of that shown in Fig. 1, the constant-pressure pipe 11 communicating with the upper end of the cylinder 25^b and the pipe 24 communicating with the lower end of the same, so that the squaring device will be lowered on exhausting pressure from the lower end of the cylinder and will be raised on admitting pressure thereto, the valve-chests 13 and 18 being likewise rearranged to permit of this action. 105

In Fig. 6 I have shown a modified construction of valve-operating device in which the lever 21^a is hung to a fixed pivot 35 and the valve-stems 16 and 16^a are connected to a cross-lever 36 and which is hung to the inner end of the operating-lever 21^a by means of a link 37. In this case the connection between the cross-lever 36 and the stem 16 will serve as the fulcrum until the valve in the chest 18 reaches the limit of its movement in either direction, whereupon the connection between the lever 36 and stem 16^a becomes the fulcrum and further movement of said lever is imparted to the valve-stem 16. 110

Having thus described my invention, I claim and desire to secure by Letters Patent—

1. The combination in a riveting or punching machine, of a main cylinder having a piston with rod carrying a riveting tool or punch, a squaring device, a supplementary cylinder having piston with rod connected to said squaring device, a valve-chest with valve for controlling the flow of motive fluid to and from the main cylinder, a valve-chest with valve of less diameter than the first for controlling the flow of motive fluid to and from

the supplementary cylinder, a lever connected to the stems of said valves, and provision for operating said lever whereby it will have its fulcrum first upon the stem of one valve and then upon the stem of the other valve.

2. The combination in a riveting or punching machine, of a main cylinder having a piston with rod carrying the riveting tool or punch, a squaring device, a supplementary cylinder with piston having a rod connected to said squaring device, a valve-chest having a valve for controlling the flow of motive fluid to and from the main cylinder, a second valve-chest having a valve of smaller diameter than

the first for controlling the flow of motive fluid to and from the supplementary cylinder, and a single operating-lever engaging directly with the stems of said valves, whereby it fulcrums first upon one and then upon the other of said stems.

In testimony whereof I have signed my name to this specification in the presence of two subscribing witnesses.

ERWIN GRAVES.
